UNITED STATES PATENT OFFICE.

GEORGE W. MCKINNEY, OF CHESTER, PENNSYLVANIA.

YARN-FEEDING DEVICE.

1,360,554.

Specification of Letters Patent. Patented Nov. 30, 1920.

Application filed October 10, 1919. Serial No. 329,857.

To all whom it may concern:

Be it known that I, GEORGE W. MCKINNEY, a citizen of the United States, residing at Chester, in the county of Delaware and 5 State of Pennsylvania, have invented certain new and useful Improvements in Yarn-Feeding Devices, of which the following is a specification.

It is well known that in winding machines, such for example as machines for winding a number of ends of chain warp, that it is necessary for the operator of the machine to carefully and constantly watch the ends of warp as they move toward and 10 are wound upon the bobbins. In view of the fact that these winding machines usually contain a great number of bobbins which are spread over a comparatively wide space and are positioned in a number of tiers, it has 15 been necessary for the operator to constantly walk from one end of the machine to the other in order to attend to broken ends as they appear from time to time and, in view of the fact that the attention of the operator 20 is so widely diverted, it is impossible to quickly stop the machine or to move from one broken end to another. Thus great 25 waste of yarn occurs and in addition to this the machines are often idle while entangled 30 ends or other imperfections are remedied.

In the above mentioned type of winding machines the ends of yarn have usually been fed thereto by first passing over a top rail or beam of the machine and then downwardly to the respective bobbins. This produced a complete net work in front of the machine and as above stated the wide space rendered it practically impossible for an operator to quickly detect broken or defective ends of the yarn while passing to the 40 bobbins.

One object of my invention is to provide improved means, for feeding yarn to winding machines, which will be so constructed 45 and arranged that it will reduce waste of yarn and time and will also economize space.

Another object is to make my invention of a simple and durable construction and so that the operator can easily detect any imperfections in the yarn and quickly stop the 50 operation of the machine.

A still further object is to so construct my invention that the ends of yarn will enter the winding machine from one end thereof 55 in the direction of the length of the machine and so that the ends of yarn can be inspected

while occupying a comparatively narrow space across which the operator can easily reach for the purpose of removing any imperfections of yarn which might occur as the 60 latter passes to the winding machine.

These objects, and other advantageous ends which will be described hereinafter, I attain in the following manner, reference being had to the accompanying drawings in 65 which—

Figure 1 is a front elevation showing my improved yarn feeding device in connection with a winding machine,

Figs. 2 and 2^a show a view of similar nature to Fig. 1 and drawn on an enlarged scale illustrating the parts more in detail,

Figs. 3 and 3^a represent a top plan view of Figs. 2 and 2^a,

Fig. 4 is a transverse sectional elevation 75 taken on the line 4—4 of Fig. 2^a and drawn on an enlarged scale,

Fig. 5 is a fragmentary top plan view of Fig. 4,

Fig. 6 is a fragmentary perspective view 80 of certain of the parts of my invention, and

Fig. 7 is an elevation of a dividing or combing reed which I preferably employ.

Referring to the drawings, 8 represents a winding machine having a plurality of tiers 85 9, 10 and 11, each of the tiers having two rows 12 and 13 of spindles upon which bobbins 14 are mounted. These spindles are rotated by means of belts 15 which pass over drums 16 arranged at different elevations, as clearly shown in Fig. 4. A motor 17 is illustrated as operatively connecting the drums 16 for the purpose of rotating the drums. A number of lifter rods 18 are adapted to be raised and lowered by mechanism not illustrated and said mechanism can be of the type usually employed in winding machines for raising and lowering the lifter rails and yarn guides. For example the lifter rods 18 can be guided and operated by any well known means such for example as the guiding and operating devices disclosed in United States Patent, No. 1,137,514.

Channels 19 extend longitudinally between the rows 12 and 13 of spindles of each of the tiers 9, 10 and 11, and these channels have yarn guides 20 and 21 secured to their sides as clearly shown in Fig. 6.

A stand 22 is preferably made of frame 110 work and includes a standard 23 which has a large eyelet or guide 24 at its top. A num-

ber of pins 25 extend outwardly from the standard 23 below the guide 24 and provide a rack 25^a. A beam 26 is pivoted between its ends at 27 to the stand 22 and has transverse rungs 28 spaced apart and located at one side of the pivot 27. The rails 29 of the stand 22 has bars or rungs 30 extending therebetween and below the rungs 28 of the beam 26, as clearly shown in Fig. 2. The 10 ends 31 of the yarn are grouped and pass through the guide 24 and then in a zig-zag manner alternately between the pins 25 of the rack 25^a. After leaving the rack 25^a the group of ends pass downwardly under one 15 of the rungs 30 and then upwardly over one of the rungs 28 of the beam 26, then downwardly under another one of the rungs 30 and again upwardly over the other rung 28 of the beam 26. From the latter mentioned 20 rung 28 the ends pass downwardly to the other of the rungs 30 and then upwardly over a roller 32. The beam 26 at the opposite side of the pivot 27 is preferably notched as shown at 33 and a suspended 25 weight 34 is adapted to engage any of the notches 33 at various distances from the pivot 27; said weight serving to move the rungs 28 of the beam 26 upwardly away from the rungs 30 and thereby place tension 30 on the ends of yarn.

A second stand 35 is interposed between the end of the winding machine 8 and the stand 22. This stand 35 has two rollers 36 and 37 journaled in its top, and a bracket 38 projects from the stand 35 toward the stand 22. The bracket 38 includes a substantially horizontal arm 39 which is V-shape in top plan view as shown in Figs. 3 and 3^a. The arm 39 forms a support for a 40 dividing or combing reed 40, said reed having splits 41 between which the ends of yarn 31 respectively pass. The reed 40, as illustrated, is in a position below a plane including the axes of the rollers 32 and 36 so 45 that the ends of yarn in passing from the roller 32 are compelled to extend downwardly through the reed and then upwardly over the roller 36, as clearly shown in Fig. 1.

The winding machine 8 has a plurality of 50 rails 42 projecting therefrom toward the stand 35 and said rails at their outer ends have collective guides or eyelets 43; said guides or eyelets 43 being in substantial alinement with the respective channels 19. 55 The ends of yarn are divided into smaller groups 44 due to the fact that a number of the ends pass through each of the guides or eyelets 43. After passing over the roller 36, certain of the smaller groups 44 pass under 60 roller 37 while others pass over said roller 37 according to the height of the guides 43 through which they must pass. Each of the channels 19 has a main eyelet 45 positioned at its end nearest the stand 35 and through these eyelets 45 the respective

groups 44 of yarn ends pass into the channels 19. After passing through the main eyelets 45 the ends of yarn pass through the yarn guides 20 and 21 on opposite sides of the channel and from thence to the bobbins 70 of the rows 12 and 13. The yarn guides 20 and 21 are not directly opposite each other as clearly shown in Fig. 5. On the contrary, the yarn guides 20 occupy a slightly advanced position so that during the winding of the respective bobbins the direction or angle of the yarn in extending from the yarn guides to the bobbins will be substantially the same at different times during the building of the tapered shape of the bobbins 75 80 as illustrated in Fig. 4.

A foot rail 46 is mounted on antifriction rollers 47 directly in front of the arm 39, and an operator standing at the side of the arm 39 can easily move the foot rail 46 lengthwise. The foot rail 46 is connected by an arm 48 to a switch 49 which controls the operation of the motor 17. Thus an operator in watching the yarn as it passes through the splits of the reed 40 can quickly 90 stop the machine 8 by a movement of the foot on the rail 46 if any imperfection of the yarn is noticed as it passes through the straight reed 40. It will be noted that the reed 40 is free to be moved lengthwise along the arm 39 for the purpose of combing or separating any ends of yarn if they should happen to become entangled and if necessary the reed 40 can be bodily lifted from the arm 39 to facilitate the combing action. 95

During the feeding of the yarn the channels 19 with the yarn guides 20 and 21 thereon receive an upward and downward movement due to the action of the lifter rods 18 to cause the yarn to be fed to the bobbins 100 throughout their height. Furthermore by arranging two rows of bobbins in each tier and providing a single channel 19 therebetween a great number of bobbins can be 105 operated in a comparatively small space and with comparatively few operating parts since the limiting rods of each tier cause the feeding of the yarn to two rows of bobbins. In addition to this, the inclusion of the 110 channels provides a housing for the ends of yarn and confines smaller groups 44 within a limited space free of any projections and so as to provide a smooth surface with which the ends of yarn can contact without injury thereto. 115

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims. 125

Having thus described my invention, what 130

I claim as new and desire to secure by Letters Patent is:—

1. A winding machine including a row of winding elements; a collective guide arranged adjacent the end of said row; means located adjacent the end of the machine for delivering yarn in the direction of the length of said row through said collective guide whereby a group of ends passes substantially parallel to said row; and other guides spaced apart for directing the ends from said group to the respective winding elements; substantially as described.
2. The combination with a winding machine including rows of winding elements arranged in tiers; collective guides adjacent the ends of each tier; means for separating the ends of yarn, said ends after being separated passing in groups through said guides and other guides spaced apart within the length of the tiers for guiding the ends from said groups to the respective winding elements of each tier; substantially as described.
3. The combination with a winding machine including rows of winding elements; collective guides adjacent the ends of each row; a dividing reed through which the ends of yarn pass and are thereby separated, said ends after being separated passing in groups through said guides and other guides spaced apart within the length of the rows of winding elements for guiding the ends from said groups to the respective winding elements of each row; substantially as described.
4. The combination with a winding machine including rows of winding elements arranged in tiers; collective guides adjacent the ends of each tier; a dividing reed through which the ends of yarn pass and are

thereby separated; means for supporting the ends of yarn at each side of said reed and at a higher level than said reed, said ends after being separated by said reed passing in groups through said collective guides; and other guides spaced apart within the length of said tiers for guiding the ends from said groups to the respective winding elements of each tier; substantially as described.

5. The combination with a winding machine including rows of winding elements; collective guides adjacent the ends of each row; a dividing reed through which the ends of yarn pass and are thereby separated, said ends after being separated passing in groups through said reeds, other guides spaced apart within the length of said rows of winding elements for guiding the ends from said groups to the respective winding elements of each row; and means forming a support for said reed over which the latter can be moved; substantially as described.

6. The combination with a winding machine including adjacent rows of winding elements; a channel extending longitudinally between said rows and having yarn guides thereon; said channel being movable relatively to said winding elements whereby the yarn guides are moved to feed yarn to said elements of each row; and means for directing the ends of yarn into said channel in the direction of its length; substantially as described.

In testimony whereof I have signed my name to this specification in the presence of two subscribing witnesses.

GEORGE W. MCKINNEY.
